UNITED STATES PATENT OFFICE.

JAMES J. FURLONG, OF TACOMA, WASHINGTON.

COLLAR FASTENER.

Application filed August 29, 1921. Serial No. 496,378.

To all whom it may concern:

Be it known that I, JAMES J. FURLONG, a citizen of the United States, residing at Tacoma, in the county of Pierce and State 5 of Washington, have invented new and useful Improvements in Collar Fasteners, of which the following is a specification.

This invention comprehends the provision 10 of a collar fastener adapted for use at the back of the neck band of the shirt, the fastener being of novel design to permit the collar to be quickly and easily attached to the shirt or removed therefrom, and when attached to hold the collar from riding or 15 moving upwardly on the collar band.

The nature and advantages of the invention will be better understood when the following detailed description is read in connection with the accompanying drawings, 20 the invention residing in the construction, combination, and arrangement of parts as claimed.

In the drawings forming part of this application, like numerals of reference indicate similar parts in the several views and 25 wherein:

Figure 1—is a fragmentary view of a collar band of a shirt showing the collar fastener associated therewith.

Figure 2—is a fragmentary rear elevation, 30 showing the collar partly broken away with the fastening device in position.

Figure 3—is a view showing the initial position of the button incident to associating 35 it with the neck band of a shirt.

Figure 4—is a vertical sectional view through a collar band and a collar showing the device in use.

Figure 5—is a perspective view of the 40 fastener.

Figure 6—is a vertical sectional view through the fastener.

Figure 7—is an edge elevation partly in 45 section.

Referring to the drawings in detail, 10 indicates the neck band of a shirt which is provided with the usual button hole 11. The collar is indicated at 12 and is provided with a button hole 13, the latter being illustrated 50 as vertically disposed in this particular instance.

The fastener forming the subject matter of the present invention comprises a plate 14

which is elongated and slightly curved to conform to the curvature of the neck band 55 and collar, and thereby provide for the comfort of the wearer. The plate 14 is rounded on its ends and adapted to be arranged beneath the collar band as illustrated, while the tongue 15 projecting from the lower edge 60 of the plate is adapted to be arranged exteriorly of the collar band, after being passed through the button hole 11. The tongue 15 is offset at its point of juncture with the plate as at 15' so that the tongue 65 may be properly positioned for use. In other words, when the tongue 15 is passed through the button hole 11, it lies substantially in a plane parallel with the neck band. In order to prevent the collar from riding 70 upwardly on the neck band of the shirt, the tongue 15 is provided with lateral extensions 16 projecting from the opposed edges of the tongue, and which extensions 16 together with the tongue 15 are passed through the 75 button hole of the collar as illustrated. In practice, the plate 14 is arranged beneath the neck band of the shirt with the tongue and extensions arranged exteriorly thereof after being passed through the button hole 80 11 of said neck band. In order to facilitate the association of the collar with the shirt, the fastener is arranged initially in the manner illustrated in Figure 3 by inserting the fastener in the button hole of the neck band 85 with the tongue 15 positioned as shown. The tongue can then be readily passed through the button hole 13 of the collar, and the collar subsequently turned to bring the button hole 13 thereon in parallel relation to the 90 extensions 16, after the tongue 15 has been passed through the button hole of the collar. The extensions can then be easily passed through the button hole 13 of the collar, after which the tongue is then moved to its 95 normal position as shown in Figure 4, and the collar turned to position the button hole 13 in right angular relation to the extensions 16. The fastener is very simple in construction and can be manufactured and sold 100 at a very nominal cost.

While it is believed that from the foregoing description the nature and advantages of the invention will be readily apparent, I desire to have it understood that I do not 105 limit myself to what is herein shown and de-

scribed, and that such changes may be resorted to when desired as fall within the scope of what is claimed.

What I claim is:

5. The collar fastener of the class described comprising an arcuate shaped plate rounded on its ends, an off set portion inclined for horizontal connection intermediate the ends of the plate, a tongue depending from the

off set portion and being broadened at its 10 free end and lateral extensions projecting horizontally from the opposite sides of the tongue at the juncture of the off set portion with the tongue for the purpose specified.

In testimony whereof I affix my signature.

JAMES J. FURLONG.
